CLAIM

The ornamental design for a process chamber shower head, as shown and described.

DESCRIPTION

FIG. 1 is a top, front, left side isometric view of a process chamber shower head, showing our new design.

FIG. 2 is a bottom, rear, right side isometric view thereof.

FIG. 3 is a left side elevation view thereof.

FIG. 4 is a right side elevation view thereof.

FIG. 5 is a front elevation view thereof.

FIG. 6 is a rear elevation view thereof.

FIG. 7 is a top plan view thereof.

FIG. 8 is a bottom plan view thereof.

FIG. 9 is an enlarged portion view taken from encircled portion, "FIG. 9," in FIG. 8.

FIG. 10 is a cross-sectional view taken along line 10-10 in FIG. 7; and,

FIG. 11 is an enlarged portion view taken from encircled portion, "FIG. 11," in FIG. 7.

The even dashed broken lines represent unclaimed environment and form no part of the claimed design. The dash-dot lines represent the boundary lines of the enlarged portion views of FIGS. 9 and 11 shown in FIGS. 7, 8, 9 and 11 and form no part of the claimed design.
